William B. Durgin of Concord No. 16.

Des. 2470

Letter Patent No. 2470. Dated Sept 25, 1866

Design for a Fork or Spoon Handle.

The schedule referred to in this Letter Patent and making part of the same.

To whom it may concern:

Be it known that I, William B. Durgin of Concord in the County of Merrimack and State of New Hampshire, have originated and designed a new Pattern for Forks & Spoons; of which the following is a full, exact and clear description, reference being had to the accompanying photographs, making part of this Specification in which:

Fig. 1, is a photograph of the back of a fork of any design, and,

Fig. 2, is a photographic view of the front thereof.

I make my Fork Spoons of silver or other metal, and the handles thereof in the shape indicated in the views referred to. The upper, or broad extremity of the handle is ornamented with the scroll work represented in the drawings, and terminates at "a", in a strawberry blossom. At "b", a strawberry with three leaves in base relief. At "c", a bud all in strawberry blossoms and leaves in base relief. At "d", a blossom with leaves in base relief, all as shown in the photographs herewith transmitted.

What I claim as my invention and desire to secure by Letter Patent is: The Design for the shape of the handles of forks and spoons as indicated in the photographic drawings herewith.

Witness,

Chas. C. Sunds

W. W. Hunt,

Wm. B. Durgin.
